United States Patent Office.

JAMES E. DEAN, OF CANAAN, CONNECTICUT.

Letters Patent No. 78,072, dated May 19, 1868.

IMPROVEMENT IN MILK-CANS.

The Schedule referred to in these Letters Patent and making part of the same.

TO ALL WHOM IT MAY CONCERN:

Be it known that I, JAMES E. DEAN, of Canaan, in the county of Litchfield, in the State of Connecticut, have invented a new and improved Method of Protecting Milk in Milk-Cans from the heat of the summer atmosphere; and I do hereby declare that the following is a full and exact description thereof, reference being had to the accompanying drawings, and to the letters of reference marked thereon.

The nature of my invention consists in providing a milk-can with an adjustable metallic case, which case has a lining adhered to it, of felt or other non-conducting substance, and is clasped to the can in a manner to be removed, and again adjusted at the convenience of the user.

To enable others skilled in the art to make and use my invention, I will proceed to describe its construction and operation.

I use galvanized iron or other suitable sheet metal, a strip about as wide as the height of the body of the can, and two inches longer than its circumference; form it to the can, then attach it with dove-tail clasps, as shown at C D, Figure 1, in the accompanying drawings.

All the inside surface B, Figure 2, of the case A, except two inches of one end for joint-lap, I cover with a lining of felt or other non-conducting substance, and, with starch or other adhesive matter, adhere the felt to the metal. I make the clasps C D D, three for each case, the movable part C of a strip of sheet metal, about four inches long, tapering from two inches to one and one-half inch in width; the parts D D, each of a strip of metal about two inches wide, the same length of the part C. Turn both edges of the part C and one edge of each of the parts D D one-fourth of an inch, forming a lock; then fasten the parts D D to the case by riveting or soldering, or both, in position, to draw the case tight around the can by slipping on of the part C to the parts D D.

Thus I form a case for a milk-can that is readily adjusted or removed, which I attach when the season requires the milk to be kept cooler than the atmosphere, and which I remove while the animal heat is being taken from the milk, or when otherwise required.

What I claim as my invention, and desire to secure by Letters Patent, is—

The adjustable metallic case A, lined with felt or other non-conducting substance adhered to it, or without the lining, and the adjusting of it with the movable clasp C D D, substantially as and for the purpose set forth.

JAMES E. DEAN.
